US00D799046S

(12) **United States Design Patent** (10) **Patent No.:** **US D799,046 S**
(45) **Date of Patent:** **** Oct. 3, 2017**

(54) **APPARATUS WITH EQUIPMENT FOR ANALYZING THE EYES**

(71) Applicant: **DAVALOR SALUD, S.L.**, Tajonar (ES)

(72) Inventor: **Juan José Marcos Muñoz**, Tajonar (ES)

(**) Term: **15 Years**

(21) Appl. No.: **35/500,391**

(22) Filed: **Jun. 19, 2015**

(80) **Hague Agreement Data**

Int. Filing Date: **Jun. 19, 2015**

Int. Reg. No.: **DM/086932**

Int. Reg. Date: **Jun. 19, 2015**

Int. Reg. Pub. Date: **Dec. 25, 2015**

(51) **LOC (10) Cl.** **24-00**

(52) **U.S. Cl.**

USPC **D24/172**

(58) **Field of Classification Search**

USPC D24/172, 146, 186, 137, 160, 177; D10/46, 104.1; D16/130; 351/222, 221,

Primary Examiner — Rhea Shields

(57) **CLAIM**

The ornamental design for the apparatus with equipment for analyzing the eyes, as shown and described.

DESCRIPTION

1. Apparatus with equipment for analyzing the eyes

1.1 : is a perspective view of my new design;

1.2 : is a front view thereof;

1.3 : is a left side view thereof; and

1.4 : is a back view thereof.

In the drawings, the broken lines are for the purpose of illustrating environment only and form no part of the claimed design.

1 Claim, 4 Drawing Sheets
